UNITED STATES PATENT OFFICE.

PHILIP O'REILLEY AND FRANK G. FREESE, OF PHILADELPHIA, PENNSYLVANIA.

EXTENSION-TOOL.

No. 821,527.

Specification of Letters Patent.

Patented May 22, 1906.

Application filed December 24, 1904. Serial No. 238,219.

To all whom it may concern:

Be it known that we, PHILIP O'REILLEY and FRANK G. FREESE, citizens of the United States, residing at Philadelphia, Pennsylvania, have invented certain Improvements in Extension-Tools, of which the following is a specification.

The object of our invention is to provide a supplementary tool which can be introduced between a high-speed air or steam-driven tool and a tap or nipple, so that this class of tools can be used for tapping and driving nipples into holes in plates.

Our invention is particularly adapted for use in tapping of holes and the placing of nipples in steam-boilers, such as locomotives, where heretofore the holes for the nipples were tapped by hand and the nipples were forced in the tapped holes also by hand, making it a tedious and expensive operation and also making it necessary to calk the joint between the nipple and the boiler-plate.

By our invention we are enabled to rapidly and accurately tap the hole and drive the nipple in with such force that calking is unnecessary, and we do not destroy the efficiency of the air-tool for other purposes.

Referring to the accompanying drawings, Figure 1 is a perspective view of our improved extension-tool. Fig. 2 is a sectional view, and Fig. 3 is a sectional view showing a boiler-plate with a nipple and stay-bolt in place.

A is a casing having a handle B, extending from one end. This handle in the present instance is screw-threaded and is screwed in one end of the casing. The handle can be of any length and is grasped by one of the operatives to prevent the casing from turning when the other mechanism is applied.

40 Mounted in the casing is a spindle D, which extends through the lower portion of the casing and is provided with a square or other shaped opening d, to which the shaped end of the tap or nipple holder C can be applied.

45 Mounted on the upper end of the spindle D is a pinion E, which extends through a bearing a in the casing. This pinion has a head e, which is internally screw-threaded to receive the driving-spindle of the pneumatic or other tool, which is ordinarily driven at a high rate of speed. The periphery of this extension is preferably hexagonal in shape, so that a wrench can be applied, if necessary. In the present instance the pinion E is loose on the

spindle D and is held in place by a headed screw d', which is screwed in the end of the spindle. Secured to the lower portion of the spindle D is a gear-wheel F of greater diameter than the pinion E.

55 Mounted in the casing is a stud G, having a head g at one end and threaded at the opposite end to receive a nut g'. Loose on this stud is a pinion I, which meshes with the gear-wheel F, and secured to the extended hub i of this pinion is a gear-wheel H, which meshes with the pinion E, so that when power is applied to the pinion it is transmitted from the pinion to the gear-wheel H, from the gear-wheel to the pinion I, as it is connected with it, and from the pinion I to the 70 pinion F, which is secured to the spindle D. Thus the speed is considerably reduced while the power is increased at the spindle, so that a high-speed air-tool of light power can be used for tapping and for forcing the nipple 75 into the boiler-plate. This forcing of the nipple into the boiler-plate requires considerable power and would necessitate rather an elaborate machine of large size to accomplish the object which we attain in a smaller machine by the introduction of our extension-tool.

80 Referring to Fig. 3, M is the boiler-shell, which has a threaded opening for the reception of a nipple N, which has a tapered portion n and a straight portion n', both the straight and tapered portions being threaded, as illustrated. The interior of the nipple is cupped to receive the head m' of the stay-bolt m and is provided with a cap N', which is 90 screwed onto the straight portion n', the tapered portion of the nipple being screwed into the boiler-shell by our improved tool. The nipple-holder C has a squared portion c at one end fitting the opening d in the end of the spindle D, and has a flange at the opposite end which in the present instance is formed by screw-threading the head c' and applying thereto a nut c², which has a thread which meshes with the straight portion n' of the nipple N. This nut is firmly secured to the head c' by a pin or key. Projecting from the end of the nipple-holder is an extension c³, which is arranged to fit the seat in the nipple, so that when the nipple is screwed into the nut the extension will rest against the seat and hold the nipple rigidly, preventing it from stripping the thread when the nipple

is driven into the boiler-head. The tap for cutting the screw-thread in the boiler-plate has a squared extension which fits the cavity d in the spindle D.

5 The operation of the tool is as follows: The portable pneumatic tool has a threaded spindle to which is applied the screw-threaded head e of the pinion E. Usually two men hold the pneumatic tool in proper position,

10 while a third man holds our improved tool by the handle B so as to prevent it from rotating when power is applied. The tap is then attached to the spindle D of our improved tool, power is applied, and the pneumatic tool is

15 driven at a high speed, but the tap is driven at a comparatively slow speed through the intervention of our improved tool. After the tap has threaded the hole in the boiler-plate it is removed and the nipple-holder C is applied to the tool, as shown in the drawings, and the nipple attached to the end of the nipple-holder by screwing it into the nut c^2 until the extension c^3 seats itself. The nipple is then introduced into the threaded opening in

20 the boiler-plate and power is applied, and the nipple is driven until the nut c^2 comes in contact with the outer surface of the boiler-plate or until the tool will not drive it farther into the plate, which is sometimes the case. Then

25 our improved tool is detached from the nipple, holder and the nipple-holder backed off from the nipple. When the nipple is in place, a stay-bolt is passed through it, as shown in Fig. 3, and the cap N' is applied. It will be

30 seen that we are enabled by a very simple and compact tool to adapt a machine for use

35

to tap a hole or to introduce a nipple into a plate, which heretofore was incapable of such use, and while we have shown our improved tool adapted for use in connection with the 40 nipples of boiler-plates it will be understood that the invention can be used in any place where it is desired to reduce a high-speed machine without having to design a special and cumbersome tool for this purpose. 45

We claim as our invention—

The combination in an extension-tool of a casing, a handle therefor, a driven spindle projecting from one end of the casing, a pinion having a head projecting from the other 50 end of the casing and mounted on said spindle so as to be removable from the casing by movement in the line of the spindle, a screw carried by one of the members comprised by the pinion and the spindle for normally preventing removal of the pinion from said spindle while allowing it to turn freely thereon, a stud extending through the casing at one side of the spindle, a gear-wheel and a pinion mounted on said stud, the gear-wheel meshing 55 with the pinion on the driven spindle, and a gear-wheel secured to the driven spindle and meshing with the last-mentioned pinion, substantially as described.

In testimony whereof we have signed our 60 names to this specification in the presence of two subscribing witnesses.

PHILIP O'REILLEY.
FRANK G. FREESE.
